UNITED STATES PATENT OFFICE.

EDWIN W. WEBB, OF CHICAGO, ILLINOIS, ASSIGNOR TO STANDARD CAR TRUCK COMPANY, OF CHICAGO, ILLINOIS, A CORPORATION OF NEW JERSEY.

SIDE BEARING.

1,355,198.

Specification of Letters Patent.

Patented Oct. 12, 1920.

Application filed January 14, 1920. Serial No. 351,442.

To all whom it may concern:

Be it known that I, EDWIN W. WEBB, citizen of the United States, residing at Chicago, in the county of Cook and State of Illinois, have invented certain new and useful Improvements in Side Bearings; and I do hereby declare the following to be a full, clear, and exact description of the invention, such as will enable others skilled in the art 10 to which it appertains to make and use the same.

My invention relates to side bearings for cars of the type employing rockers interposed between the truck and body bolsters, 15 and has for its object to provide a highly efficient and simple spring-centering device therefor.

To the above end, the invention consists of the novel devices and combinations of devices hereinafter described and defined in the claims.

In the accompanying drawings, which illustrate the invention, like characters indicate like parts throughout the several views.

25 Referring to the drawings:—

Figure 1 is a view principally in longitudinal central section, with the rockers centered;

Fig. 2 is a view corresponding to Fig. 1, 30 with the exception that the rockers and spring-centering device have been moved to one extreme position;

Fig. 3 is a view in transverse section taken on the line 3—3 of Fig. 1;

35 Fig. 4 is a bottom plan view;

Fig. 5 is a view partly in plan and partly in horizontal section taken on the line 5—5 of Fig. 1;

Fig. 6 is a perspective view of one of the 40 rockers; and

Fig. 7 is a perspective view of one of the followers.

The numerals 8 and 9 indicate, respectively, the body bolster and the truck bolster 45 of a railway car.

The improved side bearing is carried by the bolster body 8 and, as shown, includes a cast rectangular housing 10 made up of upper and lower sections detachably connected by nut-equipped bolts 11. Formed with the upper section of the housing 10 are perforated flanges 12, through which may be inserted rivets or other fastening means, not shown, to rigidly secure the side bearing 55 to the body bolster 8. The lower section of

the housing 10 is open at its bottom and the top section of said housing extends over the top thereof.

In the under face of the upper section of the housing 10, is a recess 13, in which is 60 mounted a bearing plate 14, the marginal edge portions of which rest on the upper edge of the lower section of the housing 10 and is held in position thereon by a flange 15 integrally formed with the said lower 65 section of the housing. In the sides of the lower section of the housing 10, at the intermediate portions thereof, are formed outwardly extended recesses 16, the bottoms of which afford a pair of opposite guide flanges 70 or rails 17. The side walls of these recesses 16 afford stops 18. A bearing plate 19 is secured to the top of the truck bolster 9.

Interposed between the bearing plates 14 and 19, is a pair of rockers 20 located the one 75 in advance of the other. These rockers 20 are provided with apertures 21, which are aligned in the direction of the rocking movement of said rockers. Cast with each rocker 20 is a steel pin 22, which extends transversely through the respective aperture 21. Formed with the rockers 20, within the apertures 21 and at the ends of the pins 22, are two flat faces or surfaces 24, which extend both above and below said pins. 80

Supported on the guide flanges 17 is a pair of followers 25, which extend between the rockers 20. The ends of the followers 25 are extended toward each other at 26 to afford a longer bearing surface of said followers and the guide flanges 17 and thereby hold said followers in upright positions. At the intermediate portions of each follower 25 is a hub 27, in which is formed an open seat 28 that extends completely through said 90 follower. On the outer faces of the followers 25, at the seats 28, are flat bearing faces 29, which normally engage the faces 24 on the rockers 20, for a purpose that will presently appear. 100

Loosely supported in the seats 28, with freedom for a limited endwise movement, is a link 30 having at its ends hooks 31 in which rest the pins 22, thereby connecting the two rockers 20 with freedom for rocking movement. A coiled spring 32 encircles the hubs 27 and link 30, re-acts against the followers 25 and normally and yieldingly holds the same with their surfaces 29 pressed against the inner surfaces 24 of the rockers 110

20. When the followers 25 are thus engaging the rockers 20, the ends of said followers are held by the spring 32 against the stops 18, as best shown in Fig. 5. By extending 5 the coöperating surfaces 24 and 29 both above and below the axis of the spring 32, the rockers 20 are yieldingly but firmly held centered in upright positions, as shown in Fig. 1.
- 10 When the truck and body bolsters are moved to carry the rockers 20 into an extreme position, as shown in Fig. 2, the right-hand follower 25 remains in engagement with the right-hand stops 18, and the left-hand follower 25 is moved toward the right-hand follower 25 by the movement of the left-hand rocker 20. This movement of the left-hand rocker 20 causes the lower horizontal edges of its inner flat surfaces 24 to 15 swing to the right on the arc of a circle and forces the engaged follower 25 to the right and thereby compresses the spring 32. In case the truck and body bolsters swing back to their normal positions, without the body 20 bolster lifting sufficiently to carry the rockers 20 out of engagement with said truck bolster, the rockers 20 and centering device therefor will again assume their normal positions. But, in case the body bolster 25 25 should lift, when the rockers 20 are in a position as shown in Fig. 2, sufficiently to carry the rockers 20 out of engagement with the bearing plate 19, the spring 32, re-acting against the held or right-hand follower 25, 30 will move the left-hand follower back to its normal position against the left-hand stop 18 and, at the same time, center the left-hand rocker 20 under the action of the coöperating surfaces 24 and 29. The centering 35 of the left-hand rocker 20 automatically returns the right-hand rocker 20 to normal position by means of the link 30.

When the rockers 20 are lifted from the bearing plate 19, the same are supported by 45 their pins 22 from the hooked ends of the link 30 and it is important to note that said pins are located considerably above their centers of gravity, which materially assists in centering the rockers 20. In actual construction, there will be sufficient play between the pins 22 and the hooks 31, when 50 the rockers 20 are supported on the bearing plate 19, to permit the tops of said rockers to move out of engagement with the bearing plate 14 when the rockers 20 are 55 lifted from the bearing plate 19. The outwardly curved lower edge of the housing 10, at the ends thereof, affords stops with which the rockers 20 engage to limit their rock- 60 ing movement.

What I claim is:—

1. In a side bearing, the combination with upper and lower bearing plates, of a pair of rockers interposed between the bearing plates, and a spring-centering device re-act-

ing against the opposing faces of the rockers with a force tending to center the same.

2. In a side bearing, the combination with upper and lower bearing plates, of a pair of rockers interposed between the bearing plates, a link connecting the rockers, and a spring encircling the link and re-acting against the opposing faces of the rockers above and below the axis of the spring with a force tending to center the rockers. 75

3. In a side bearing, the combination with upper and lower bearing plates, of a pair of rockers interposed between the bearing plates, a link connecting the rockers and supported in respect to the upper bearing plate with freedom for endwise movement, and a spring encircling the link and re-acting against the opposing faces of the rockers above and below the axis of the spring with a force tending to center the rockers. 80

4. In a side bearing, the combination with upper and lower bearing plates, of side plates secured in respect to the upper bearing plate, a pair of rockers interposed between the bearing plates, a pair of followers mounted on the side plates between the rockers, stops limiting the movements of the followers, a link connecting the rockers and supported on the followers with freedom for endwise movement, and a spring re-acting against the followers, said followers normally engaging the rockers above and below the axis of the link to center the same. 85

5. In a side bearing, the combination with upper and lower bearing plates, of side plates secured in respect to the upper bearing plate, a pair of rockers interposed between the bearing plates and having transverse pins, a link pivotally connecting said pins, a pair of followers mounted on the side plates between the rockers and supporting the link with freedom for endwise movement, stops limiting the movements of the followers, and a spring re-acting 100 against the followers, said followers normally engaging the rockers above and below the axis of the link to center the same. 105

6. In a side bearing, the combination with upper and lower bearing plates, of side plates secured in respect to the upper bearing plate, a pair of rockers interposed between the bearing plates and having transverse pins, a link having hooks at its ends in which the rocker pins rest, a pair 110 of followers mounted on the side plates between the rockers and supporting the link with freedom for endwise movement, stops limiting the movement of the followers, and a spring re-acting against the followers, 115 said followers normally engaging the rockers above and below the axis of the link to center the same. 120

7. In a side bearing, the combination with upper and lower bearing plates, of side 130

plates secured in respect to the upper bearing plate, a pair of rockers interposed between the bearing plates and having transverse pins, a link pivotally connecting said pins, a pair of followers mounted on the side plates between the rockers and having open seats in which the link is mounted with freedom for endwise movement, stops limiting the movement of the followers, and a spring re-acting against the followers, said followers normally engaging the rockers above and below the axis of the link to center the same.

8. In a side bearing, the combination with upper and lower bearing plates, of side plates secured in respect to the upper bearing plate, a pair of rockers interposed between the bearing plates and having transverse pins, a link pivotally connecting said pins, a pair of followers mounted on the side plates between the rockers and having hubs with open seats in which the link is mounted with freedom for endwise movement, stops limiting the movement of the followers, and a spring encircling the link and hub and re-acting against the followers, said followers normally engaging the rock-

ers above and below the axis of the link to center the same.

9. In a side bearing, the combination with upper and lower bearing plates, of side plates secured in respect to the upper bearing plate, a pair of rockers interposed between the bearing plates and having apertures alined in respect to the direction of movement of the rockers, each of said rockers having a pin extending transversely through its apertures, a link having hooks at its ends in which the rocker pins rest, a pair of followers mounted on the side plates between the rockers and supporting the link with freedom for endwise movement, stops limiting the movement of the followers, and a spring re-acting against the followers, said followers normally engaging the rockers above and below the axis of the link to center the same.

In testimony whereof I affix my signature in presence of two witnesses.

EDWIN W. WEBB.
